UNITED STATES PATENT OFFICE.

EDWARD R. STETTINIUS, OF CHICAGO, ILLINOIS, ASSIGNOR TO THE
STIRLING COMPANY, OF SAME PLACE.

WATER-TUBE BOILER.

SPECIFICATION forming part of Letters Patent No. 669,772, dated March 12, 1901.

Application filed March 3, 1900. Serial No. 7,216. (No model.)

To all whom it may concern:

Be it known that I, EDWARD R. STETTINIUS, a citizen of the United States, residing at Chicago, in the county of Cook and State of Illinois, have invented a new and useful Improvement 5 in Water-Tube Boilers, of which the following is a specification.

The object of my invention is to improve the vertical water-tube boiler of the type commonly known as the "Stirling" boiler; and the invention consists in the features and combinations hereinafter described and claimed.

In the accompanying drawings, Figure 1 is a cross-section of my improved boiler, the 15 middle elevated steam and water drum, front lower mud-drum, and connecting circulating-pipe being shown in end elevation and the circulating-pipe being outside the wall or setting; Fig. 2, a longitudinal sectional elevation of the boiler, showing the circulating-pipes inside the boiler-setting; and Fig. 3, a similar view showing the circulating-pipes embedded in the walls or setting.

A, A', and A² are elevated steam and water 25 drums, a pipes communicating between the steam-spaces thereof, and a' pipes communicating between the water-spaces of the front and middle ones thereof; B, lower mud-drums; C, banks of tubes connecting the elevated 30 steam and water drums with the lower mud-drums; D, circulating-pipes connecting the ends of the middle elevated steam and water drum with the ends of the front lower mud-drum; E, the fireplace and e a fire-brick arch 35 over the same, and F fire-brick partitions in rear of and adjacent to the front and middle banks of tubes, respectively.

The Stirling type of boiler, to which my invention relates, is so well known that I do not 40 consider it necessary to describe its construction or operation in detail. In this view, and because they are clearly shown in the drawings, no description is considered necessary of the elevated steam and water drums and connecting-pipes, lower mud-drums, banks of 45 tubes connecting the lower mud-drums with the elevated steam and water drums, fire-brick arches and partitions, and other features in common use as parts thereof. In addition to these parts or features, however, I 50 provide special circulating-pipes between the

middle elevated steam and water drum and the front lower mud-drum, which circulating-pipes communicate with these drums at or near their ends, respectively, and are embedded in the walls or setting of the boiler or placed inside or outside thereof, as desired. 55 In Fig. 1 the circulating-pipe is shown outside the wall or setting, and its mate at the other end, when two are used, is to be arranged 60 in the same way. In Fig. 2 both the circulating-pipes are shown inside the wall or setting, and in Fig. 3 they are both shown embedded in the wall or setting. As already stated, 65 these pipes communicate with the end portions of the drums to which they are attached, respectively; but their connections are not necessarily at the extreme ends of the drums, connection near the ends being sufficient. 70 As shown, feed-water is to be introduced into 75 the rear mud-drum; but it may be introduced into the rear elevated steam and water drum or elsewhere, as desired.

In filling, the feed-water being introduced into the rear mud-drum passes up through 75 the rear and middle banks of tubes into the rear and middle elevated steam and water drums, and from the middle steam and water drum it passes down through the circulating-pipes to the front mud-drum and thence 80 up through the front bank of tubes to the front elevated steam and water drum, also from the middle steam and water drum through the connecting-pipes to the front steam and water drum. In operation, the 85 front bank of tubes being in the hottest part of the boiler, the most rapid upward circulation will be through this bank; but the circulating-pipes permit a constant downflow and supply of water to take the place of water converted into steam in the front bank 90 of tubes and also the place of water passing from the front steam and water drum into the middle steam and water drum or elsewhere. The water-spaces of the front and 95 middle steam and water drums communicating with each other, water passes from one of these drums to the other as required by circulation and other conditions. In other words, the circulating and connecting pipes 100 provide for a powerful circulation of water up the front bank of tubes and across from

the front steam and water drum to the middle steam and water drum and down to the front mud-drum, and so on in circuit, the practical effect being that the tubes of the 5 front bank are more completely filled with cooler water or water free from steam and transmission of heat in this bank thereby greatly increased. In addition to this primary circulation there are local circulations 10 in the tubes of the middle and rear banks, respectively, and these local circulations serve to heat the feed-water, and thereby provide for separation and a settlement of scale-forming matter in the rear and cooler parts 15 of the boiler. If feed-water be introduced in the rear or middle steam and water drum or elsewhere in the rear part of the boiler, the circulation will be practically unchanged.

The circulating-pipes being of larger diameter than the diameter of the tubes of the several banks and being located in a comparatively cool part of the boiler provide for a constant and abundant supply of water from the rear part of the boiler to the front 25 part, and this without having serious counter-currents in the tubes furnishing the heating-surface and primarily intended for the generation of steam.

Although I have shown and described one 30 circulating-pipe at each end of the boiler, it will be understood that one or more may be used, as desired. It will also be understood that instead of two circulating-pipes, one at each end, a single circulating-pipe may be 35 used at one end only.

I claim—

1. In a water-tube boiler, the combination 40 of a front elevated steam and water drum, a middle elevated steam and water drum, a rear elevated steam and water drum, pipes communicating between the steam-spaces of said

drums, respectively, pipes communicating between the water-spaces of the front and middle of said drums, a front lower mud-drum, a rear lower mud-drum, banks of tubes 45 connecting the rear mud-drum with the middle and rear steam and water drums, respectively, a bank of tubes connecting the front mud-drum with the front steam and water drum, a circulating pipe or pipes at or near 50 the ends of and communicating between the middle steam and water drum and front mud-drum located in cool relation to the boiler-setting and giving an auxiliary circulation between the two drums at the end, means for introducing feed-water, and means for drawing off steam, substantially as described.

2. In a water-tube boiler, the combination of a front elevated steam and water drum, a middle elevated steam and water drum, a rear elevated steam and water drum, pipes communicating between the steam-spaces of said drums, respectively, pipes communicating between the water-spaces of the front and middle of said drums, a front lower mud-drum, a rear lower mud-drum, banks of tubes 60 connecting the rear mud-drum with the middle and rear steam and water drums, respectively, a bank of tubes connecting the front mud-drum with the front steam and water 65 drum, a circulating-pipe at each end of and communicating between the middle steam and water drum and the front mud-drum located inside the boiler wall or setting, and giving an auxiliary circulation between the 70 two drums at each end, means for introducing feed-water, and means for drawing off steam, substantially as described.

EDWARD R. STETTINIUS.
